(57) **CLAIM**

The ornamental design for a personal hygiene device, as shown and described.

DESCRIPTION

FIG. 1 is a perspective view of a personal hygiene device showing our new design.

FIG. 2 is a top view of the personal hygiene device showing our new design.

FIG. 3 is a front view of the personal hygiene device showing our new design.

FIG. 4 is a right side view of the personal hygiene device showing our new design.

FIG. 5 is a left side view of the personal hygiene device showing our new design.

FIG. 6 is a rear view of the personal hygiene device showing our new design.

FIG. 7 is a bottom view of the personal hygiene device showing our new design.

FIG. 8 is a perspective view of a personal hygiene device having a detached spray wand showing our new design.

FIG. 9 is a top view of the personal hygiene device having a detached spray wand showing our new design.

FIG. 10 is a front view of the personal hygiene device having a detached spray wand showing our new design.

FIG. 11 is a right side view of the personal hygiene device having a detached spray wand showing our new design.

FIG. 12 is a left side view of the personal hygiene device having a detached spray wand showing our new design.

FIG. 13 is a rear view of the personal hygiene device having a detached spray wand showing our new design; and,

FIG. 14 is a bottom view of the personal hygiene device having a detached spray wand showing our new design.
